UNITED STATES PATENT OFFICE.

WILLIAM E. GIBBS, OF EAST ORANGE, NEW JERSEY.

LIQUID-FUEL BURNER.

Application filed November 4, 1921. Serial No. 512,864.

To all whom it may concern:

Be it known that I, WILLIAM E. GIBBS, a citizen of the United States, and a resident of East Orange, in the county of Essex and State of New Jersey, have invented new and useful Improvements in Liquid-Fuel Burners, of which the following is a specification.

This invention relates to liquid fuel burners and has for its principal object to provide a burner which will completely and smokelessly burn the cheaper grades of petroleum, generally known as fuel oils.

A further object is to suppress the roaring noise which usually accompanies the operation of liquid fuel burners.

With these objects in view my invention consists primarily of a burner in which a plate or pan is provided to which liquid fuel may be supplied and burned thereon, the hot products of combustion being conducted to and across the under side of the plate or pan, air being conducted to the combustion chamber through a duct whose walls are swept by the hot products of combustion. A reverberatory and regenerative action is thus brought into play which keeps the burner-head (plate and combustion chamber walls) red hot and pre-heats the air on its way to the combustion chamber. Under these conditions complete and smokeless combustion of low grade fuel oils may be effected, the tarry residuums and particles of carbon being wholly consumed.

A further improvement consists in supplying only a portion of the air to the region of the burner plate, the remainder of the air required for complete combustion of the oil vapors being admitted to the exhaust flue at a point beyond the burner plate. By this means the roaring of the burner is diminished and the burner-head kept hotter.

Still another feature of my invention resides in providing the burner plate or pan with a layer of pervious material, preferably a finely comminuted refractory substance such as sand, which layer acts as a wick to distribute the liquid fuel over the surface of the plate and prevents the fuel from assuming the spheroidal state.

Other features will be pointed out in the following detailed description of two illustrative embodiments of my invention.

In the drawings, Fig. 1 is a diagrammatic longitudinal vertical section (partly in elevation) of a simple form of my invention;

Fig. 2 is a horizontal section taken through the centre of the air duct in Fig. 1, parts being shown in plan; Fig. 3 is a perspective view (parts being broken away) of a preferred embodiment of my invention; Fig. 4 is a vertical section; and Fig. 5 is a plan view of the same.

Referring to the construction shown in Figs. 1 and 2, 8 is a blower, preferably driven by an electric motor 10, and having a discharge pipe 3 which is prolonged to form an air duct passing through the secondary combustion chamber 2. The air duct 3 terminates adjacent the upper surface of burner plate or pan 5 in the primary combustion chamber 1.

The two combustion chambers are closed at one end by a rounded wall 1^a which serves to deflect flames originating on top of the plate 5 to and across the under side of said plate and eventually into the exhaust flue 7 which may discharge into a suitable chimney or stack.

A fuel supply pipe 4, having any suitable controlling device such as a valve 9, has its lower end raised a little from the plate 5 and feeds oil to the plate by gravity. A layer of sand 11 (previously referred to) is spread over the surface of the plate for the purpose previously mentioned. Preferably the plate 5 is slightly inclined outwardly so that the liquid fuel will flow along it from right to left.

In the exhaust flue 7 grate bars 17 are disposed for the purpose of supporting a coarse bed 7^a of broken fire brick or the like.

The operation of the burner is as follows: The flow of oil is started and as soon as it has saturated the sand on top of the burner plate it is ignited by a torch or other flame introduced through the opening under the hinged cover 16. The cover is then closed and the blower is started, whereupon the flames from the burning oil (for which the sand acts as a wick) are driven by the heated air currents across the upper surface of the plate and are deflected by the wall 1^a to the under side of the plate, and into the exhaust flue, where said flames play on the air duct 3, thereafter passing through the bed of broken fire brick and issuing out of the top of the fire pot. In a short time the burner plate and air duct become red hot and the flame that then issues from the fire pot is white and smokeless.

I have found that the broken fire brick in the exhaust flue, by subdividing the current of gases, materially diminishes the roaring noise which would otherwise be of objectionable loudness.

In Figs. 3, 4 and 5 a practical form of my burner is illustrated, which may be made of cast iron, or, as shown, the external walls of the fire pot may be composed of fire brick. 10 The top wall is provided with a large exhaust opening and a smaller air port is provided in the right hand end wall. In this embodiment the burner plate is supported by a sheet metal partition 15 which closes off the combustion chamber from the exhaust flue 7. A similar partition 15' has a vertical portion which forms another wall of the exhaust flue and an extension which projects laterally beneath the burner plate and 20 curves up around the outer end of the burner plate. It will be observed that the partition 15' separates the exhaust flue from the air port and forms the inner wall of an enveloping air duct which leads air to the 25 upper side of the burner plate. The partition 15' is made preferably of iron or other metal or material which is a good conductor of heat, in order to facilitate the transfer of heat from the hot gases in the 30 combustion chamber 2 to the air in the air duct.

As previously stated, improved results are obtained if the air supply is divided, somewhat less than the entire amount of 35 air required for complete combustion being conducted to the region of the burner plate; for in this way, the burner-head may be maintained at a higher temperature and roaring will be appreciably reduced. With 40 these ends in view, I provide perforations 12 in the partition 15' for admitting auxiliary air to the combustion chamber 2 at a point where such auxiliary air will not impinge upon the burner plate 5. For controlling the relative proportions of the main 45 and auxiliary supplies of air a damper 13 having perforations complementary to the perforations 12 is provided, preferably with means external to the furnace for manipulating the damper, such as a handle 13'. By properly adjusting the damper 13 conditions 50 can be established in which surface combustion will take place in the broken fire brick. This mode of operation will be advantageous for some purposes, for example, where 55 the burner is used as a forge or to heat melting pots.

Except as specifically described above, the construction and operation of the embodiment shown in Figs. 3, 4 and 5 are the same as have previously been pointed out in connection with Figs. 1 and 2. It is contemplated that my improved burner may be inserted in any existing furnace designed for 60 burning solid fuel, resting on the usual grate

bars of such a furnace. Any suitable device for preliminarily igniting the fuel may be employed such as for example, a continuously burning pilot flame of gas. Moreover, any of the usual thermostatic devices 70 may be used to control the oil and air supplies but these are not shown or described as they do not form a part of my invention.

Claims:

1. A liquid fuel burner comprising a 75 burner plate, means for supplying liquid fuel and preheated air to the upper side of said plate and means for conducting the products of combustion to the under side of said plate.

2. A liquid fuel burner comprising a burner plate, means for supplying preheated air under pressure and liquid fuel to the upper side of said plate, and means for conducting the products of combustion to 85 the underside of said plate.

3. A liquid fuel burner comprising a burner plate, means for supplying liquid fuel to the upper side of said plate, an air conduit discharging to the upper side of 90 said plate, and a conduit conducting the products of combustion to and across the under side of said plate, said two conduits being contiguous, whereby the air in the first mentioned conduit absorbs heat from 95 the products of combustion in the last mentioned conduit.

4. A liquid fuel burner comprising in combination, a furnace having an inlet port for air and a flue opening for products of 100 combustion, of a burner plate disposed within said furnace, and means for supplying liquid fuel to said plate, and a partition separating said port and flue and terminating near said plate.

5. A liquid fuel burner comprising in combination, a furnace having an inlet port for air and a flue opening for products of 110 combustion, of a burner plate disposed within said furnace, means for supplying liquid fuel to said plate, and a heat conducting partition separating said port and flue and terminating near said plate.

6. A liquid fuel burner comprising in combination, a combustion chamber, a burner plate constituting a baffle in said combustion chamber, means for supplying liquid fuel to said plate, an air duct discharging to the upper side of said plate, and an exhaust flue communicating with the under side of said plate.

7. A liquid fuel burner comprising in combination, a combustion chamber, a burner plate having three of its edges only in contact with the walls of the combustion 125 chamber, means for supplying liquid fuel to said plate, an air duct discharging to the upper side of said plate, and an exhaust flue communicating with the under side of said plate.

8. A liquid fuel burner comprising in combination, a combustion chamber, a burner plate having three of its edges only in contact with the walls of the combustion chamber, means for supplying liquid fuel to said plate, an air duct discharging to the upper side of said plate, and an exhaust flue communicating with the under side of said plate opposite to the edge of said plate which is spaced from the walls of the combustion chamber. 50
9. A liquid fuel burner comprising in combination, a fire pot, a burner plate constituting an incomplete partition in said fire pot, and forming upper and lower combustion chambers, means for supplying liquid fuel to said plate, a second partition beneath and spaced from said plate and having an upturned portion extending between an edge of said plate and the wall of the fire pot, said second partition constituting the outer wall of the upper and lower combustion chambers and constituting the inner wall of an enveloping air passage, a port admitting air to said air passage, and an exhaust flue communicating with said lower combustion chamber. 60
10. A liquid fuel burner comprising in combination, a combustion chamber, a burner plate in said combustion chamber, means for supplying liquid fuel to said burner plate, and exhaust flue communicating with said combustion chamber, and an air duct enveloping said combustion chamber and communicating therewith. 65
11. A liquid fuel burner comprising in combination, a combustion chamber, a burner plate constituting an incomplete partition in said fire pot, means for supplying liquid fuel to said plate, an air duct discharging to the upper side of said plate, and an exhaust flue communicating with the under side of said plate. 70
12. A liquid fuel burner comprising in combination, a burner plate, means for supplying liquid fuel to said plate, means for heating said plate, means for supplying air to the region of said plate, means for pre- 75
- heating the air before it reaches the plate, an exhaust flue, and an auxiliary air inlet in said flue. 80
13. A liquid fuel burner comprising in combination, a furnace having an inlet port for air and an exhaust flue, a burner plate disposed within said furnace, means for supplying liquid fuel to said plate, and a partition separating said port and flue and terminating near said plate, said partition having ports for admitting auxiliary air into said flue. 85
14. A liquid fuel burner comprising in combination, a fire pot, a burner plate constituting an incomplete partition in said fire pot and forming upper and lower combustion chambers, means for supplying liquid fuel to said plate, a second partition beneath and spaced from said plate and having an upturned portion extending between an edge of said plate and the wall of the fire pot, said second partition constituting the outer wall of the upper and lower combustion chambers and constituting the inner wall of an enveloping air passage, a port admitting air to said air passage, and an exhaust flue communicating with said lower combustion chamber, said second partition having ports for admitting auxiliary air into said flue. 90
15. A liquid fuel burner comprising in combination, a combustion chamber, a burning plate in said chamber, means for supplying liquid fuel and air to said plate, an exhaust flue communicating with the combustion chamber, and a coarse pervious bed of refractory material in said flue. 95
16. A liquid fuel burner according to Claim 14 having an adjustable inlet for auxiliary air in the flue between the burning plate and the bed of refractory material.

The foregoing specification signed at 90
Orange, N. J., this 3rd day of Nov., 1921.

WILLIAM E. GIBBS.
